United States Patent

Des. 239,925
Patented May 18, 1976

239,925

INSTRUMENT FOR GUIDING THE DRAWING OF DESIGNS

Morton P. Matthew, Kreiner Lane, R.F.D. 2,
Norwalk, Conn. 06850

Filed Nov. 5, 1973, Ser. No. 412,753

Term of patent 14 years

Int. Cl. D10—99

U.S. Cl. D10—61

Fig. 1.

Fig. 2.

FIG. 1 is a top plan view of an instrument for guiding the drawing of designs showing my new design, the rear being identical therewith;

FIG. 2 is an edge elevational view thereof.

I claim:

The ornamental design for an instrument for guiding the drawing of designs, as shown and described.
